(57) **CLAIM**

The ornamental design for a portable ultrasound medical device as shown and described.

DESCRIPTION

FIG. 1 is a top-front-left perspective view of a portable ultrasound medical device according to the claimed design shown in an opened configuration.

FIG. 2 is a top-rear-left perspective view of the portable ultrasound medical device shown in the opened configuration.

FIG. 3 is a right side view of the portable ultrasound medical device shown in the opened configuration.

FIG. 4 is a left side view of the portable ultrasound medical device shown in the opened configuration.

FIG. 5 is a front view of the portable ultrasound medical device shown in the opened configuration.

FIG. 6 is a rear view of the portable ultrasound medical device shown in the opened configuration.

FIG. 7 is a top view of the portable ultrasound medical device shown in the opened configuration.

FIG. 8 is a bottom view of the portable ultrasound medical device shown in the opened configuration.

FIG. 9 is a top-front-left perspective view of the portable ultrasound medical device shown in a closed configuration; and,

FIG. 10 is a bottom-rear-right perspective view of the portable ultrasound medical device shown in the closed configuration.

The portable ultrasound medical device is adjustable between the opened configuration shown in FIGS. 1-8 and the closed configuration shown in FIGS. 9-10. The control features of the portable ultrasound medical device are

(Continued)

accessed in the opened configuration and the portable ultrasound medical device is securely transported in the closed configuration.

The broken lines in the drawings illustrate portions of the ultrasound medical device that form no part of the claimed design.

1 Claim, 10 Drawing Sheets
